SECURING MEANS FOR OUTBOARD MOTORS

Michael D. Consolo, Wilkinsburg, and George V. Clanton, Jamestown, Pa.; said Consolo assignor to said Clanton

Application June 18, 1948, Serial No. 33,788

1 Claim. (Cl. 248—25)

1 The invention relates to securing devices for outboard motors of boats.

Outboard motors for boats commonly comprise screw clamp devices for detachably mounting the motor on the transom or stern-board of a boat and usually the clamping device has two clamping screws. In service these clamps are subjected to severe vibration and stresses and consequently there is considerable tendency for the clamps to loosen and permit dismounting and injury of the motor apparatus. If dismounting occurs when a boat is traversing deep water there is danger of irretrievable loss of the motor and, even if a submerged motor be recovered, an expensive over-haul is necessary to put it in satisfactory working condition.

The general object of the present invention is to provide securing means capable of cooperation with the mounting means of a conventional outboard motor to prevent the detachment and even substantial displacement of the mounting means in relation to a boat transom on which the motor is mounted.

It is also an object of the invention to provide securing means suitable for use with motor mounting devices differing considerably in form and construction.

Another object of the invention is to provide securing means for outboard motors adapted for use on boats having different forms of stern construction.

A further object of the invention is to provide a lockable securing means for outboard motors constructed to permit the locking means used with the securing means to serve to lock the motor in inoperative position with its propeller raised out of the water.

It is also an object of the invention to provide a securing device for outboard motors that cannot readily be tampered with.

Another object of the invention is to provide securing means of the character specified that is simply constructed, of light weight, amply strong, easily manipulated in use and susceptible of manufacture at low cost.

With the foregoing and other ancillary or incidental objects in view the invention consists in certain forms, combinations and arrangements of parts hereinafter described and explained with reference to the accompanying drawings and defined in the appended claim.

In the drawings:

Fig. 1 is a front elevation of an outboard motor and a portion of a boat transom showing the motor provided with the securing means of the present invention.

2

Fig. 2 is a side elevation of the apparatus shown in Fig. 1 with the major part of the motor proper broken away and with said motor and its driven shaft swung to a horizontal position so that the propeller and rudder (which are broken away and omitted from the drawing) are raised in known manner to a position above the water level.

Fig. 3 is a fragmentary sectional view taken on the line 3—3 of Fig. 1.

Fig. 4 is a fragmentary sectional view taken on the line 4—4 of Fig. 1.

Figs. 5 and 6 are face and side elevation views, respectively, of one of the parts of the securing means.

Fig. 7 is a front elevation showing a modified form of boat transom and a correspondingly modified construction of the securing means embodying the invention, a large part of the outboard motor being omitted in this view.

Fig. 8 is a side elevation of the apparatus shown in Fig. 7.

Fig. 9 is an enlarged front elevation of a portion of the securing means shown in Fig. 7 arranged for use in connection with a plain boat transom such as is shown in Figs. 1 and 2.

Fig. 10 is a front elevation of securing means of a third form of construction.

Referring in detail to the construction illustrated in the drawings and first to the form shown in Figs. 1—4, 11 designates as an entirety a boat motor of outboard type and conventional construction. This outboard motor comprises the motor proper 12, a shaft-enclosing sleeve 13 rigidly attached to the frame of motor 12, a motor-driven shaft 14 within the sleeve 13, and a mounting bracket 15 in which the sleeve 13 is swivelled. To permit illustration on a larger scale the lower parts of the sleeve 13, shaft 14 and the usual rudder and propeller associated with these parts have been broken away and omitted since the present invention is not concerned with them.

The mounting bracket 15 of the motor is provided, in accordance with the usual practice, with a pair of clamps 16 which are swivelled on oppositely facing trunnions of bracket 15 and secured on the trunnions by a through-bolt 17. Each of the clamps 16 comprises a long arm designed to engage the outer face of the boat transom or stern-board 18 and a shorter arm fitted with a hand-operated clamp screw 19 which comprises a disc or washer 19a swivelled on the end thereof to engage the inner or front face of the transom.

The motor is provided with tiller arm 20 which is jointed so that the handle end can be swung

up to inoperative position in the manner shown in Fig. 1.

An outboard motor constructed and mounted in the manner described is subjected in operation to severe vibratory stresses under which the wood of the boat transom has its fibers worn or compacted by the clamping screws with resultant tendency of the screws to loosen. If such loosening of the clamps is not quickly observed and remedied there is serious danger, under severe pounding of waves or engagement with a submerged bar or obstruction, that the motor may be torn loose and lost overboard. To prevent a happening of this character the present invention provides securing means for the motor which make impossible a separation of the motor from the boat transom.

As shown in Figs. 1-4 the securing means comprise a staple device 21 (Figs. 4, 5 and 6) comprising a base plate 22 and a loop 23 rigidly riveted to it. The staple is constructed to be strongly secured to the front face of the transom 18 by means of screws 24, 24.

Arranged to cooperate with staple 21 is a hasp 25 slotted to pass over the loop 23 of the staple. Two pairs of elongated links or tension members 26, 26 have their apertured lower ends pivotally connected by rivets 27, 27 to the hasp 25, and these tension members 26 are formed at their free ends with hooks 26a, 26a which are designed to partially embrace one or the other of the screws 19 of the mounting clamps 16. To effectively secure the hasp 25 on the staple 21 a padlock 28 is provided with shackle 28a to engage the staple.

It will be understood that in the attachment of the securing means to the boat transom, the outboard motor having been mounted on the transom in the usual manner and secured by tightening the clamps, the tension members or links 26 are hooked over the clamp screws in the manner indicated in Figs. 1 and 2 and, with the staple yet unattached to the transom but assembled with the hasp, the proper position of the staple can be marked on the transom. The hasp and attached links 26 can then be removed from the staple and the latter secured in its marked position with the screws 24. With the staple thus mounted it is apparent that any substantial movement upward of the motor clamps in relation to the transom 18 is prevented by the securing means.

Different makes of outboard motors and different sizes of motors of the same make vary more or less as to the spacing of the dual clamping screws and it will be appreciated that the construction of our securing means is particularly well adapted to meet such differences in motor design. Because of the pivotal connection of the tension members 26 to hasp part 25 the members can swing parallel to the plane of the hasp and the securing means adapts itself automatically to a considerable variation of clamp screw spacing.

In Fig. 2 of the drawing the propeller of the motor has been swung upward out of the water and the motor has been turned (in mounting bracket 15) to bring the tiller 20 in line with or directly in front of the staple 21. This permits the shackle 28a of the padlock 28 to embrace the tiller arm 20 so that the lock serves effectively both to lock the outboard motor to the boat and to secure the motor in its inoperative position. This feature of the invention is a factor which to some extent affects the design of the secur-

ing means since the combined length of the hasp and link parts of the device needs to be such as to locate the staple on the transom at a point adjacent to the tiller arm when it is swung down to the inoperative position shown in Fig. 2.

It will be observed on comparison of Figs. 1, 4 and 5, that the hasp 25 when locked in position on the staple 21 effectively prevents access to and tampering with the securing screws 24, 24.

The embodiment of the invention shown in Figs. 1 and 2 is particularly suitable for use with boats having plain transoms or sternboards. For use with transoms having stern posts a form of the invention such as is shown in Figs. 7 and 8 is provided. Here the transom 31 is fitted with a stern post or brace 32 which is straddled by the motor mounting clamps 16 and which prevents the use of a single anchoring staple in the manner shown in Figs. 1 and 2. Accordingly, as shown in Fig. 7, two such staples 21 are mounted, one on either side of the stern post 32. For cooperation with each staple there is provided a hasp 25' to which one pair of links 26, 26 are pivotally connected by rivet 27. As in the case of the first described construction the links 26 have their free ends formed with hooks 26a to engage the screws of the motor clamps 16. Each staple is provided with a securing padlock 28 and either of the two locks can be employed to lock the tiller arm of the motor with the latter in inoperative position as shown in Fig. 2.

The securing means 25', 26 shown in Figs. 7 and 8 can be employed in lieu of that shown in Figs. 1 and 2, as will be apparent from inspection of Fig. 9 showing the tension bars 25 spread in position to engage the screws of the two motor clamps. Naturally when this form of construction is to be used in the manner last referred to the parts should be made with adequate strength to secure both clamps of the motor instead of one only.

It will be readily appreciated that the forms of construction which have already been described can be varied in carrying out the invention. One such variation is shown in Fig. 10 in which the hasp 25 is fitted with links 33 having their free ends enlarged at 33a and apertured to pass over the swivelled discs of the clamping screw and engage the stem of the screw, each of the parts 33 being pivotally secured by a rivet 34 to the hasp 25. It will be apparent that the links 33 of this last-described construction, as well as the links 26 of the other constructions, have at their free ends a downwardly open loop formation to receive and embrace a screw shank of the motor clamp.

From an inspection of the several forms of construction of the securing means it will be apparent that they are simply constructed, easy to manipulate and use and can be produced at moderate cost, many of the parts of the securing means being designed to be stamped from sheet metal. By forming the parts of steel of suitable quality for hardening they may be given great strength and a degree of hardness suitable to discourage tampering by unauthorized persons. The formation and arrangement of the hasp member so as to prevent access to the securing screws of the staple device has already been noted.

It will be observed also that the securing means are so designed as to be effectively secured to the anchoring staple by the padlock when the

motor is not mounted on the boat as well as during use of the motor and thus there is little likelihood of misplacement or loss of any part of the securing means.

It is to be understood that practice of the invention is not intended to be limited to the particular embodiments of the invention which have been specifically illustrated and described but that the invention can be embodied in other essentially equivalent forms.

What is claimed is:

Lockable securing means for outboard boat motors having dual-screw clamping means with downwardly open jaws constructed to embrace the top edge part of a boat transom, the said securing means comprising a staple device having an opening and constructed to be fixedly secured to the inner face of a boat transom and means separate from the staple device for disengagably connecting the screws of such a clamping means to the staple, said separate means including a flat hasp part apertured to pass over the staple and leave the opening of the latter exposed to receive the shackle of a padlock and a plurality of elongated links each pivotally con-

5

nected at one end to the hasp for movement parallel to the plane of the hasp, the free ends of the links having hook formations to engage the clamp screws.
